UNITED STATES PATENT OFFICE

JIM D. E. WASHINGTON, OF KANSAS CITY, MISSOURI, ASSIGNOR OF ONE-HALF TO DIXON
E. WASHINGTON, OF KANSAS CITY, MISSOURI

ROTARY PUMP OR MOTOR

Application filed January 12, 1927. Serial No. 160,696.

This invention relates to mechanical devices especially designed for use in connection with the transmitting of power either through the method of driving the main shaft upon which the rotor of the machine is mounted, or through the method of exerting the energy or driving power directly against the pistons of the piston assembly which, in turn drives the main shaft in a manner which permits of taking the power therefrom.

The broad object of the instant invention contemplates improvements in machines or devices of the above-mentioned character which remove the objections usually found in such structures. Some of these objections are obviated by the neutralization of all objectionable centrifugal forces which are usually set up at various speeds, concentric mounting of the main piston assembly in the chamber of the housing to eliminate excessive radial throws and the use of a floating piston assembly which floats within the chamber of the housing and remains in concentric relation to the annular wall thereof at all times.

An even further object of this invention is the provision of a floating piston assembly which includes a means for hingedly interconnecting all the pistons thereof at their inner ends and within the main rotor of the device.

Many minor objects will appear during the course of the following specification, which sets forth in detail one form of the device which is universal in its application in that it may be used effectively as rotary motor, a compressor, a meter for high pressure gases, pressure motor for all liquids and high pressure gases, pump for all fluids and gases, water meter, booster in gas lines, hydraulic transmission, hydraulic safety stop for elevators or the like, vacuum pump and a blower or exhauster. These applications are merely set forth as an example of the scope covered by the simple structure shown in the accompanying drawings which show the preferred form of the invention and in which,

Figure 1 is a side elevation of the device made in accordance with the invention.

Fig. 2 is an enlarged vertical cross section of the same taken on line II—II of Fig 1.

Fig. 3 is another vertical central section taken on line III—III of Fig. 2.

Fig. 4 is an end view of the rotor and piston assembly showing the same entirely removed from the housing.

Fig. 5 is a side view of the same.

Fig. 6 is a fragmentary face view of the intake and exhaust slots, and

Fig. 7 is a perspective view of one piston, showing the same removed from its operative position and entirely separated from its hinge.

Similar reference characters have been used to designate like parts throughout the several views, and the numeral 8 designates the main housing having a chamber 9 formed therein which may be closed by heads 10 and 12 respectively. These heads may be bolted or otherwise secured to housing 8 as shown at 13, and each should be provided with bearings 14 and 14' adapted to support a rotor R.

It is to be noted that in practicing this invention, the bearings 14 and 14' should be formed to support the rotor R in eccentric relation to the annular wall of chamber 9. In this device, the rotor R and the chamber 9 each have true annular walls, and no cam surfaces or the like are present.

With particular reference at this time to the construction of the rotor which may be made of any suitable metal of a strong and durable character, the same may be formed of a main body ring 15 closed at its two ends by plates 16 all of which provides a hollow rotor R. Each plate 16 should have a projection 17 integral therewith which engages bearings 14 and 14', and one projection continues in the form of a main shaft 18 extending exteriorly of the device. Any suitable stuffing box 19 may be used as shown in Fig. 2. When the rotor R is in place as illustrated in Figs 2 and 3, the outer periphery of the annular wall of ring 15 should engage the inner surface of annular wall of housing 8. In this manner, a cavity is formed which increases in size as its greatest size is approached. This point of greatest size being diametrically opposite the point of contact just set forth.

The piston assembly of this device includes a plurality of pistons 20, all of equal length and all hingedly interconnected at a center, within the rotor, which is concentric with the center of the chamber 9 of housing 8 and eccentric to the center of rotor R. In hingedly connecting these pistons 20, it is desirable to use a hollow pin 21 of a length substantially equal to the distance between the inner surfaces of plates 16. This precludes longitudinal movement of the pin 21. Each piston 20 has hinge-pin engaging lugs 22 formed integrally thereon, and the assembly at this point may be termed a "piano hinge" construction.

As above stated, the pistons 20 are all of equal length, and Fig. 3 clearly shows that the outer ends ride over the annular wall of housing 8. To properly receive and transmit power, the pistons are sealed where they pass through rotor R through the use of split shaft members 23, carried by rotor R in any suitable manner to permit rotation about their centers as the machine or device is operated. In this way, a floating piston assembly is utilized, the pistons of which hinge about a common center and maintain a proper working relation as the rotor R rotates about a fixed center. The center of the piston assembly is not fixed to any part of the device. Slots 23' are formed in rotor plates 16 into which slots members 23 engage at each end thereof. Projections 20' are formed on pistons 20 and these projections extend into and through slots 23' as far as casing heads 10-12. As shown in Fig. 4, slots 23' are of sufficient length to permit projections 20' to reciprocate the desired amount.

In the instance shown, two passages 24 and 25 respectively have been illustrated, each of which leads to the cavity formed between the rotor and the annular wall of the housing chamber. Through these passages, the fluid, gas, or other substance as the case may be passes. The actual ports at the ends of these passages are formed of slots 26 which, if desirable may be staggered with relation to each other to preclude undue wearing at the ends of the pistons 20.

As one example of oiling the parts of this universal device, a gear oil pump 27 is shown which may be used to supply oil to the interior of the rotor R through passage 28 which terminates in a pocket 29 large enough in diameter to always be in communication with the hollow 30 formed in pin 21. To equalize pressure, slots 31 are provided in each piston 20. The size of these slots may be varied to meet conditions.

In view of the art, the operation of a device of this character is obvious. The novel features of the structure have been clearly set forth and illustrated, and it is desired to

make clear that the particular use of the mechanism is not herein limited.

What is claimed and desired to secure by Letters Patent of the United States is:

1. In a device of the general character set forth, a housing having a chamber formed therein, a hollow rotor mounted for rotation within said chamber, a piston assembly having a plurality of pistons contained within said rotor, side walls for said rotor and slots in said side walls, said pistons being hingedly interconnected at their inner ends, each projecting through corresponding slots in said walls and piston sealing means rotatably carried by said rotor and engaging said slots. 70 75 80

2. In a device of the general character set forth, a hollow rotor, side walls for said rotor and slots in said walls, a piston assembly contained within said rotor, each piston thereof extending through corresponding slots in the walls of said rotor and sealing means for each piston respectively including a split shaft journaled for rotation in the walls of said rotor and engaging in said slots. 85 90

3. In a rotary pump or motor, a casing having inlet and outlet openings, a rotor rotatably mounted in said casing and having side walls, radial slots in said walls each slot being enlarged at its inner end to form a circular opening, a series of pistons having lateral extensions located in said slots, each piston having sealing members on opposite sides thereof, the ends of said members being rotatably mounted in said circular openings. 95 100 105

In testimony whereof I hereunto affix my signature.
